UNITED STATES PATENT OFFICE.

DORA E. EILAR, OF LOVOYE, WYOMING, ASSIGNOR OF ONE-HALF TO JOHN E. WELTON,
OF BOWLING GREEN, OHIO.

GAS BURNER.

Application filed March 2, 1925. Serial No. 12,643.

This invention aims to provide a simple means whereby a mixture of gaseous fuel and any other fluid ingredients may be brought about, novel means being provided whereby the mixture may be burned, to fire boilers, furnaces, and the like, and, in general, for any purpose for which the device is adapted.

It is within the province of the disclosure 10 to improve generally and to enhance the utility of devices of that type to which the invention appertains.

Although a preferred form of the invention has been shown in the drawings, it will 15 be understood that a mechanic, working within the scope of what is claimed, may make such alterations as his skill may suggest, without departing from the spirit of the invention.

20 In the accompanying drawings:—

Figure 1 shows in top plan, a device constructed in accordance with the invention; Figure 2 is a longitudinal section; Figure 3 is an end elevation; and Figure 4 is a cross 25 section.

The device forming the subject matter of this application preferably is made of metal throughout and comprises a hollow body 1 including a cylindrical shell 2 provided in 30 termediate its ends with a fuel inlet 3, the shell 2 being closed at its rear end by a flat wall 4, and being closed at its forward end by a conical wall 5. A burner tube 6 extends through the body 1, longitudinally thereof, 35 one end of the tube projecting beyond the front wall 5, and the other end of the tube terminating flush with the rear wall 4, the tube being carried by the said walls. The space within the body 1, about the tube 6, 40 constitutes an expansion chamber 7. Perforations 8 in the burner tube 6 establish communication between the bore of the tube and the expansion chamber 7.

At its rear end, the body 1 carries a support 45 of any desired sort in the form of a spider 9, including rearwardly extended and inwardly inclined arms 10, and a hub 11 carried by the arms. A holding device 12, such as a set screw, is mounted in the hub 11 and 50 is adapted to engage a fluid supply nozzle 14 which is longitudinally adjustable in the

hub 11, the nozzle having a tapered end 15 cooperating with the rear end of the burner tube 6.

In practical operation, gaseous fuel passes 55 into the body 1 by way of the inlet 3 and expands or circulates in the chamber 7, the gas entering the burner tube 6 through the perforations 8. A fluid of any kind, such as gas, steam or air, is fed, under pressure, 60 through the nozzle 14, and, passing into the burner tube 6, through the tapered end 15 of the nozzle, creates a mixture within the tube 6, the mixture flowing to the left in Figure 2, and creating a suction through the 65 perforations 8. The mixture burns at the left hand end of the tube 6 in Figure 2. The set screw 12 forms a means whereby the nozzle 14 is held releaseably, so that the nozzle may be adjusted longitudinally, thereby enabling the nozzle to cooperate properly with 70 the rear end of the burner tube 6.

Having thus described the invention, what is claimed is:—

In a device of the class described, a hollow 75 body comprising a cylindrical shell having a lateral inlet and provided with an outwardly-extended conical front wall and with a flat rear wall, a burner tube extended through the rear wall at the axis thereof and terminated about flush with the rear wall, the tube being extended through the front wall at the apex thereof, and being prolonged therebeyond, the space about the tube and within the body forming a chamber, 80 the tube having perforations distributed throughout all of that portion of the tube which lies between the front and rear walls, the perforations establishing communication 85 between the chamber and the bore of the tube, a support projecting rearwardly from the rear end of the body, and including inclined arms and a hub carried by the arms, a fluid pressure supply nozzle adjustable 90 longitudinally in the hub, toward and away 95 from the rear end of the burner tube, and clamping means mounted in the hub, for holding the nozzle in adjusted positions.

In testimony that I claim the foregoing as my own, I have hereto affixed my signature. 100

DORA E. EILAR.
